AUTOMATIC FLAT - BOTTOM COUNTER-SINKING ATTACHMENT FOR MILLING MACHINES

Peter Shelby, Fenton, Mich.

Application September 11, 1942, Serial No. 457,998

4 Claims. (Cl. 77—4)

This invention relates to mechanism for producing flat-bottom countersinks in metal plates, blocks, etc., and is particularly well adapted for use as an attachment for milling machines, although not necessarily limited to such.

Recently there is a great need for countersinks in plates, blocks, etc. having a perfectly flat bottom with no central recess or opening and these have been produced, in the past, by rotating the work with respect to a rotating cutter. Considerable skill and time is required to produce a countersink by such procedure. As an example, one use for such countersink is to receive a pad of rubber or other resilient material as backing for sheet material being punched, the countersink being in the die of the punching equipment. Any recesses or holes in the bottoms of the countersinks have a tendency to damage the resilient pad. There are of course other uses for countersinks of this nature and the foregoing is given merely as an example to emphasize the importance of producing a flat-bottom countersink.

The principal object of the present invention is to provide a simple and efficient countersinking mechanism which is more or less automatic in its operation after the initial cut has been made and which does not require rotation of the work. By its use the time required to produce a countersink is greatly reduced, a neater job is accomplished, and machinists quickly become skilled in the use of the mechanism.

Another object of the invention is to provide means whereby the initial cut may be quickly accomplished and then the mechanism set for automatic operation until the countersink is completed.

A further object of the invention is to provide such means as may be adjusted to operate quickly and efficiently according to the characteristics of the work, that is, whether operating on hard metal or the softer metals or alloys.

A further object of the invention is to provide such mechanism as may be applied to various makes and models of milling machines without coupling any portion of the attachment to the machine except to the usual spindle and chuck.

Another object of the invention is to provide a flat-bottom countersinking tool which may be easily manufactured and quickly dismembered for adjustment or repair.

A still further object of the invention is to provide in a countersinking tool simple and efficient means for rigidly supporting and bracing the cutter or work engaging element.

Other objects and advantages of the invention will appear in the following detailed description of the preferred embodiment of my invention, taken in connection with the accom-

panying drawings, forming a part of this specification, and in which drawings:

Figure 1 is a side elevation of a suitable milling machine showing my attachment applied thereto and with a piece of work in place.

Figure 2 is a front elevation of the same.

Figure 3 is a detailed side elevation of the attachment.

Figure 4 is a view partly in elevation and partly in vertical section longitudinally of the head of the attachment.

Figure 5 is a plan view.

Figure 6 is a view similar to Figure 3 but showing the other side of the rotating part of the attachment, and showing a piece of work in place.

Figure 7 is an end elevation of the attachment.

Figure 8 is a view partly in elevation and partly in vertical section transversely of the rotating part.

Figure 9 is a dismembered view of the cutter and carrier parts in perspective.

Figure 10 is a view partly in elevation and partly in vertical section of an assembly of the cutter and carrier differing from that shown in Figure 4.

Figure 11 is a fragmentary view in elevation showing an arrangement for quick feed of the cutter with respect to the work.

Figure 12 is a dismembered view of a smaller cutter and portion of the carrier, in perspective.

Figure 13 is a perspective view showing a typical example of the work accomplished by the mechanism.

In Figures 1 to 11, inclusive, is shown a milling machine A, a piece of work B, and the mechanism C constituting the preferred embodiment of my invention. In Figure 12 is shown a tool holder part of modified form.

The milling machine A comprises a suitable base 14, a main vertical column 15, a knee 16 vertically adjustable on the column 2, as by operating crank 17, a saddle 18 slideable toward and away from column 15 on knee 16, a table 19 horizontally slideable on saddle 18 in a direction at right angles to the motion of the saddle, a spindle 20, and a chuck 21. It will be seen that the work B mounted on table 19 can be adjusted to any desired position within the limits of motion of the parts. As the above adjustment is practically universal in milling machines and in itself constitutes no part of the present invention, further details of description thereof are deemed unnecessary.

The mechanism C comprises, generally, a head 22 including a spindle 23, a tool carrier 24, a cutter or tool 25, means 26 for reciprocating the tool carrier 24 in head 22, and an actuating device 27 for operating means 26.

In addition to including the spindle or shank 23, the head 22 comprises a top plate 28, a guide block 29 and spaced bottom plates 30.

The top plate 28 is preferably elongate in shape, having rounded ends 31 and flat upper and lower faces 32 and 33, respectively. It is provided with vertical openings 34, for the reception of bolts 35 used to secure it to guide block 29; a vertical bore 36 accommodating a portion of shank 23; and, a counterbore 37 open to the lower face 33 for a disc 38 formed integral with shank 23.

Some of the bolts 35 may pass thru disc or flange 38, as shown in Figure 8 to aid in securing the shank 23 to plate 28, altho I prefer to also provide pins 39, received in openings 40 and 41 in the top plate and disc, respectively, as shown in Figure 4.

Referring to the guide block 29, it is also preferably elongate in shape to fit against the bottom face 33 of top plate 28 and conform somewhat to the contour thereof. It is provided with screw threaded bores 42 for the reception of the shanks of bolts 35, as shown in Figure 8; a slot 43 of inverted T-shaped cross section, as shown in Figure 8 with its lower portion 44 open to the bottom of the block and its upper portion 45 closed by plate 28; and a shaft bearing 46 thru one end of the block and a bearing 47 thru the other end thereof.

The bearing 47 has a shaft receiving portion 48 and a thrust portion 49 for a purpose to be subsequently set forth.

To facilitate assembly, the bottom plates 30 are provided with vertical holes 50 for bolts 51, the shanks of which are received in screw threaded recesses 52 open to the bottom of block 29. These bottom plates extend longitudinally of the lower portion 44 of slot 43 and engage the lower portion of tool carrier 24.

The bearings 46 and 47 are axially aligned and co-axial with the upper portion 45 of slot 43.

The carrier 24, in the example shown, includes an elongate body portion 53 provided with a longitudinal slot 54 open at its top 55 and bottom 56; an upstanding block 57 integral with body portion 53 and provided with a transverse screw threaded bore 58; and a set screw 59 received in an opening 60 extending thru one end of the body portion 53 and communicating with one end of slot 54. The carrier 24 also preferably includes a substantially Z-shaped filler piece and brace 61 to partially fit in slot 54, for cooperation with a suitable tool 25 having a work engaging portion 63 and a shank portion 64.

The element 61 has an upper portion in the nature of a lug 65 engaging the top of shank 64 in slot 54; an intermediate portion 66 disposed partially in the slot 54 and partially therebelow; and a lower portion in the nature of a lug 67 engaging the bottom 56 of body portion 53. Thus the lug 67 limits the upward movement of the filler piece and brace 61 in slot 54 so the upper portion of the element 61 cannot impede travel of the carrier 24 in the guide block 29. If desired, a recess 68 may be provided in a face of intermediate portion 66 above lug 67 for the reception of the inner end of set screw 59.

As shown more particularly in Figures 4 and 8, the body portion 53 is of a width and height for sliding fit in the lower portion 44 of slot 43, and the upstanding block 57 is accommodated in the upper portion 45 of slot 43, with the bore 58 of block 57 co-axial with bearings 46 and 47.

Figure 4 shows the preferred manner in which

the element 61 is used, that is, with the lug 67 engaging the bottom 56 of body portion 53, beneath set screw 59. Such an arrangement provides good surface-to-surface contact between the tool 25 and element 61, in the direction of thrust, when the tool is in use. However, in Figure 10 the position of element 61 is shown reversed, an arrangement permitting the mechanism to be used in producing countersinks of greater diameter than the arrangement in Figure 4. This is an arrangement suitable for use also where the work is not in hard metal.

In Figure 12 is shown a modified filler piece and brace 70 for use with a smaller tool 71 having a work-engaging portion 72 and a shank 73. This is substantially like element 61 except that below a top lug 74 is provided spaced flanges 75 on intermediate portion 76, providing a slot 77 for smaller shank 73.

The means 26 for reciprocating the tool carrier 24 comprises a screw 78, including shaft portion 79 in bearing 46, a shaft portion 80 received by bearing portion 48, a relatively long screw threaded portion 81 extending thru bore 58; a flange 82 engaging thrust portion 49 of bearing 47; a wheel 83 rigid with shaft portion 80 adjacent flange 82; and, retaining means 84 at the outer end of bearing 46. The wheel 83 is preferably provided with teeth 85 for cooperation with actuating device 27. The means 84 may comprise a thrust washer 86, a bolt 87 co-axial with and in threaded engagement with shaft portion 79, and a lock washer 88.

Upon rotation of wheel 83 in a clockwise direction, looking at Figure 7, the tool 25 will be fed toward the axis of shank 23, bringing into use the flange 82 and thrust portion 49 of bearing 47, since engagement of the cutter with the work has a tendency to move the tool carrier 24 away from the axis of shank 23.

Within the limits of motion of the parts, the wheel 83 may be rotated about its axis in either direction, and as the head 22 is rotated it will be noted that the wheel 83 bodily travels in a zone encircling the head. The preferred actuating device 27 for operating means 26 comprises an arm 89 normally located in a plane parallel to this zone and loosely mounted on shank 23, a rod 90 secured to arm 89 and engaging some stationary part of the machine, such as the column 15 thereof, and one or more pins 91 adjustably secured to arm 89 as by set screws 92. Each pin 91 is used to impart a partial turn to wheel 83 by engaging a tooth 85 thereof, as is obvious from Figures 7 and 11 of the drawings.

In the example shown, arm 89 has an opening 93 for the reception of shank 23, this opening being located near the middle portion of the arm. It has a sliding fit with the shank so that the arm may be bodily moved away from the position shown in Figures 3, 4, 6 and 7, but normally arm 89 is inert, and in the example shown, rests upon a washer encircling shank 23 to space the arm from the upper face of top plate 28. One end portion of arm 89 has a block 95 provided with a transverse opening 96 for the reception of rod 90, which may be held in the adjusted position by set screw 97. The other end portion of arm 89 is provided with a series of vertical openings 98 for the reception of pins 91, the set screws 92 being used in the well known manner, to hold these pins in the desired adjusted position. The series of openings 98 are along an arc concentric with opening 93 and are located so that a single pin 91, as shown in Figure 7, may be ad-

justed in one of the openings 98 so as to normally project in the zone surrounding head 22 in which wheel 83 moves during use of the attachment, and so as to engage a tooth 85 of the wheel and impart partial rotation thereto. Or, two or more of the pins 91 may be used, as shown in Figure 11, where the work is soft, so as to obtain a greater speed ratio of a step-by-step nature between the tool carrier 24 and the spindle 28 for each revolution of the head 22.

As a typical example of operation of the mechanism, assuming that the piece of work B has been secured to table 19 in any suitable manner and is free of the cutter or tool 25, the actuating device 27 may be lifted and held so that its pin or pins 91 are out of the zone of travel of wheel 83 until movement imparted to spindle 20, and raising of the knee 16 will cut a circumferential groove in the work, of the desired depth, as shown in Figure 6, whereupon the actuating device 27 may be lowered so as to function in automatically feeding the tool 25 toward the axial center of shank 23. From then on operation may be automatic. Instead of lifting the actuating device 27 as just described, it may be permitted to rest inert on washer 94, and by manipulation of set screw 92, any pin 91 in the circumferential zone of travel of wheel 83 may first be lifted so as to not actuate the wheel until the initial cut has been produced, whereupon the desired pin or pins 91 may be lowered for automatic operation.

In Figure 1 I have shown a tubular rod 99 on rod 90,—an expedient which may be used if the stationary part of the milling or other machine, such as the vertical column 15 is spaced a considerable distance from chuck 21.

It is to be noted that, according to the preferred form of my invention, the only element of the attachment, secured to the milling machine, is the shank 23, for while the actuating device 27 is normally inert and held against movement by rod 90 or rod 99 engaging some stationary part of the machine, it may nevertheless be lifted to quickly prevent feed of tool 25, and to facilitate the initial cut shown in Figure 6.

As it may be noted from Figure 13, there may be produced in the metal a flat-bottom countersink 100, having a vertical wall 101 and a perfectly flat bottom 102, free of holes or depressions, the work remaining rigid on table 19 throughout the entire operation.

By the use of this mechanism, the time for make ready has been materially reduced over present methods, but mainly the period for completing the operation has been reduced by hours. Furthermore the mechanism may be quickly adjusted for operating on different types of metals or alloys by the selection of a single pin 91 if the material is hard, or two or more of the pins according to the softer characteristics of the material.

I claim:

1. A flat-bottom countersinking attachment for milling machines and the like including a spindle having a tool receiving chuck and a stationary part spaced laterally of the axis of the chuck; a head including a shank for said chuck, a tool carrier supported by said head, reciprocable transversely of the axis of said shank, a countersink cutter supported by said carrier extending laterally of its axis of movement, a screw for reciprocating said tool carrier, a toothed

wheel on said screw located laterally of said head to rotate said screw and to bodily travel in a zone encircling said head as the spindle rotates, and an actuating device for said screw including 5 an arm normally located in a plane parallel to said zone and loosely mounted on said shank to move longitudinally thereof, a rod secured to said arm and engaging said stationary part of the machine to arrest rotation of the arm with said shank, and one or more pins carried by said arm and normally projecting in the said zone to move said toothed wheel step-by-step as the head rotates.

2. A flat-bottom countersinking tool comprising 15 a head including a top plate, a shank extending from the upper face thereof, an elongate guide block detachably secured to the lower face of said plate, provided with a slot of inverted T-shaped cross section extending longitudinally 20 of the block and transversely of the axis of said shank and a combined shaft receiving and thrust bearing member at one end of the slot co-axial with the upper portion of said slot; a tool carrier including an elongate body part guided and reciprocable in the lower portion of said slot and an upstanding block on said body portion, intermediate its ends, provided with a screw threaded bore co-axial with said bearing member, and movable in the upper portion of said slot, and 25 a feed screw for said carrier provided with a shaft portion in said bearing member, a flange engaging said thrust receiving portion of the bearing member, and a screw threaded portion extending thru said bore.

3. A flat-bottom countersinking tool comprising 30 a head including a top plate, a shank extending from the upper face thereof, a guide block detachably secured to the lower face of said plate, provided with a slot of inverted T-shaped cross section extending transversely of the axis 35 of said shank and a combined shaft receiving and thrust bearing member at one end of the slot co-axial with the upper portion of said slot; a tool carrier including an elongate body part guided and reciprocable in the lower portion of said slot and an upstanding block provided with a screw threaded bore co-axial with said bearing member, and movable in the upper portion 40 of said slot; a feed screw for said carrier provided with a shaft portion in said bearing member, a flange engaging the thrust receiving portion of the bearing member and a screw threaded portion extending thru said bore; and, spaced plates detachably carried by the bottom of said 45 guide block, extending longitudinally of the lower portion of the slot and engaging the lower portion of said body part of the tool carrier.

4. In a countersinking tool, a carrier including 50 an elongate body portion provided with a longitudinally extending slot open to the top and bottom thereof, a set screw extending thru one end of said body portion, into said slot, a cutter including a work engaging portion and a shank portion received in said slot, and a substantially Z-shaped filler piece and brace for the cutter disposed with its upper portion in said slot engaging the top of the cutter shank, its intermediate portion extending into and below said slot and engaging the cutter shank laterally, and its lower portion engaging the under side of the body portion of said carrier to limit upward movement of the filler piece and brace in the slot.

PETER SHELBY.
